UNITED STATES PATENT OFFICE.

HARRY M. CAIN, OF DENVER, COLORADO.

BUTTER-CUTTER.

SPECIFICATION forming part of Letters Patent No. 398,879, dated March 5, 1889.

Application filed July 3, 1888. Serial No. 278,976. (No model.)

To all whom it may concern:

Be it known that I, HARRY M. CAIN, a citizen of the United States of America, residing at Denver, in the county of Arapahoe and State of Colorado, have invented certain new and useful Improvements in Butter Cutters and Extractors, of which the following is a specification, reference being had therein to the accompanying drawings.

10 My invention relates to a novel device or machine for cutting butter into pats or lumps and extracting the so-cut lump or pat; and its object is to provide a simple and effective device by the use of which pats or lumps of butter may be cut in symmetrical or regular shape from larger masses of butter, such as is contained or packed in tubs, firkins, large rolls, &c., and then removed from such larger mass in such symmetrical or regular shape, 15 and which lump or pat may, if desired, be cut of a weight approximating a desired weight—a device economical in manufacture, easy of use, reliable in operation, not liable to derangement, and reliable; to which ends the 20 invention consists in the features more particularly hereinafter described and claimed.

In the drawings is illustrated an apparatus embodying the invention, in which drawings Figure 1 is a side elevation of such an apparatus; Fig. 2, a central vertical section thereof; Fig. 3, a perspective view of the knife used.

In the figures the reference-numeral 1 indicates an open-ended cylinder forming the cutting-cylinder, and of a diameter equal to the diameter desired for the pat or lump to be cut or formed, and of a depth or length equal to that of the largest pat or lump desired to be cut or formed. To enable it to be readily forced into and penetrate a mass of butter, its lower edge should be somewhat sharpened, as shown by the bevel or taper 2. At its upper edge is an internal screw-thread, 3, in which take the threads of the cap or cover 4, closing that end of the cutting-cylinder 1. Such cap or cover might be made integral with the cylinder; but the construction indicated is preferable, in that the parts may be readily disassociated when desired, the more easily and thoroughly to cleanse the operative parts. 45 From the cap 4 rises the curved loop-handle 5, secured to or formed therewith, and by

which the apparatus may be grasped for use. Within the cylinder is placed the follower head or piston 6, adapted or fitted to readily slide therein, and connected by two or more rods, 8, to a ring or washer, 7, upon the outside of the head or cap 4, the rods 8 sliding through suitable apertures left or formed therein for their passage. Passing through apertures left or formed in the follower or piston head 6, the cap 4, and the upper part of the handle 5 is a knife-rod, 9, fitted to readily move or slide in such apertures. At its lower end this rod carries the knife 10, turning in its seat upon its pivot 11, seated in the rod. 65 As shown in Fig. 3, the pivot 11 of this knife is placed at or near the thinner or cutting edge, so that normally the back or thicker or heavier edge falls to the bottom, and so that if it be attempted to turn the knife-rod and 70 knife against a resistance, as that of a mass of butter, the resistance will so swing the knife as to place the cutting-edge to the front or in the direction it is desired to turn the rod and the knife.

Above the ring or washer 7 and below the top of the handle 5 a stop-pin, 13, projects from or is passed through the rod 9, limiting the amount of its movement in either direction, while upon the upper and outer end of 80 the rod any suitable handle, 12, may be secured for the ready manipulation of the rod and its attached knife.

The operation is as follows: The handle 5 is grasped, and in such manner that the stop-pin 13 is also grasped, holding the rod 9 and knife 10 stationary, and the cylinder 1 is then forced down in the butter to the appropriate or the designated depth, the follower or piston head 6 being forced inward by the butter entering the cylinder. After the cylinder has been forced into what is deemed a sufficient depth, the knife-rod 9 is forced down until the cutting-edge of the knife is on a line or about on a line with the bottom edge of the cylinder, 95 and the rod is then turned. As before explained, the knife immediately turns on its pivot, presenting its cutting-edge, so that as the knife-rod is turned the knife sweeps in a circle whose radius is the length of the knife, 100 which is just sufficient to clear the interior of the cylinder. This cuts the butter within the

cylinder loose or away from the remaining body, and the cylinder is then withdrawn. The piston head or follower being now pushed outwardly by means of the ring 7, the butter 5 is ejected from the cylinder 1, remaining, however, between the knife 10 and the follower-head 6. The rod and knife are now drawn back through the butter to the head and the butter then cut or removed from the latter in a sym-
10 metrical pat or lump.

The cylinder 1 need not necessarily be a cylinder or circular in cross-section, but may in cross-section be of any regular symmetrical shape, and it may be gaged so as to contain 15 approximately or on the average a certain definite amount of butter. Graduations 14 may be arranged upon the rod 9 or upon the handle 5, to indicate approximately the amount of butter within the cylinder, forcing the follower 20 or head back; or the graduations may be arranged to indicate the position of the knife to cut off approximately a given weight of butter. While the cap 4 takes in an internal thread, 25 3, in the cylinder 1, it is evident that such cap may be flanged and be seated upon the cylinder by a thread upon the exterior of the

cylinder or by a bayonet-joint or any of the many known ways of securing a cap or cover to a body.

While herein, for convenience, the invention 30 is described with reference to butter, it is evident that it may be used with any other forms of fat, or with any plastic or waxy matters, or other matters into which the cylinder 1 may or can be forced.

Having thus described my invention, what I claim is—

The combination of the cylinder 1, cap 4, with attached handle 5, follower 6, ring 7, rods 8, connecting the follower and ring, knife-rod 40 9, having handle 12, and knife 10, pivoted by pivot 11 in the rod and at right angles thereto to automatically turn and present its edge in the direction of movement of the knife, substantially as set forth.

In testimony whereof I affix my signature in presence of two witnesses.

HARRY M. CAIN.
